ATTORNEY

UNITED STATES PATENT OFFICE.

ALVIN D. KEENE, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC HEATING UNIT.

Application filed January 22, 1924. Serial No. 687,719.

My invention relates to electric heating devices and particularly to relatively high-capacity flexible electric heating units.

One object of my invention is to provide an extended electric heating unit, of relatively high capacity that shall be capable of conforming to a curved surface.

Another object of my invention is to provide an electric heating unit that shall comprise a minimum number of component parts.

In practicing my invention, I provide a relatively heavy return-bent resistor member, the adjacent portions of which are engaged by spaced sets of pairs of opposed refractory members, each pair of which engage two adjacent resistor portions only. The pairs of refractory members in each set are staggered relatively to each other.

20 Means are provided to hold the heating unit against the surface to be heated.

In the single sheet of drawings,

Figure 1 is a view, in end elevation, of a heating unit embodying my invention, as applied to a cylindrical container or muffle,

Fig. 2 is a view in longitudinal section therethrough, taken on the line II—II of Fig. 1,

Fig. 3 is a top plan view of an electric heating unit embodying my invention,

Fig. 4 is a view in lateral section therethrough, taken on the line IV—IV of Fig. 3,

Fig. 5 is a top plan view of a refractory member comprising a part of a heating unit embodying my invention, and

Fig. 6 is a view in side elevation thereof.

A resistor member 11, of relatively heavy wire or rod of a suitable resistor material, such as nichrome, is preformed to comprise a plurality of straight, substantially parallel-extending, return-bent portions, substantially as illustrated in Fig. 3 of the drawing. The return bent straight portions may be of any suitable or desired length in order to permit of covering a predetermined surface therewith.

A plurality of sets of staggered pairs of refractory members 12, of electric-insulating material, are provided to hold the intermediate parts of the return-bent straight portions in proper operative positions relatively to each other. Each member 12 is of substantially trapezoidal form in longitudinal section, substantially as illustrated in Fig. 6 of the drawing. The longer face is

provided with a plurality of laterally extending grooves 13, each of substantially semi-circular shape. An opening 14 extends laterally through the body of the member 12, and an opening 15 extends longitudinally therethrough.

As illustrated more particularly in Fig. 3 of the drawing, pairs of opposed members 12 are secured together by means of bolts 16 having co-operating nuts 17 at one end thereof, which bolts extend through the aligned openings 14 and serve to hold the members 12 loosely on or around adjacent, spaced, straight portions of the resistor member 11. The pairs of members 12 are staggered relatively to each other, as is illustrated in Fig. 3 of the drawing.

It is not necessary to employ a plurality of staggered pairs of co-operating members 12 at the end of the preformed resistor member 11, by reason of the fact that the return-bent portion is sufficiently strong enough to prevent any great separation of the adjacent resistor portions. It is, therefore, sufficient to employ a single set of co-operating pairs of members 12 to hold the adjacent straight portions that are not connected at that end by the return bent portions of the resistor member, whereby the location of the pairs of members 12 is substantially as illustrated in Fig. 3 of the drawing.

If it is desired to heat a substantially cylindrical container 18, as for instance, a fluid container, or a muffle of a tubular furnace, the heating element or unit comprising the preformed resistor member and the spaced sets of pairs of refractory members may be made to conform to the curved surface by merely bending the resistor member around the curved surface. A plurality of wires or rods 19 are threaded through the aligned openings 15 in the outer set of members 12, and suitable fastening means are supplied for the ends of the wires 19, whereby the heating unit is mounted in its proper operative position relatively to a mass of solid material or of a container that is to be heat-treated.

The resistor member 11 fits loosely within the substantially circular openings provided by the opposed co-operating pairs of members 12, whereby free longitudinal expansion of the straight portions of the resistor member is permitted relatively to the intermediate sets of members 12.

The refractory members 12 cause the resistor member to be suitably spaced away from the solid mass of material or the container to be heated by the heating unit and these refractory members, therefore, serve a double purpose, in that they not only space the resistor member from a surface or container to be heated thereby, but also serve to suitably space the adjacent portions of the resistor member from each other and maintain them in such spaced positions.

Various modifications and changes may be made without departing from the spirit and scope of the invention, I desire, therefore that only such limitations shall be placed thereon as are imposed by the prior art or are set forth in the appended claims.

I claim as my invention:

1. In an electric heating unit, in combination, a relatively heavy resistor member preformed to comprise a plurality of substantially parallel-extending return-bent straight portions lying in a single plane, a plurality

of spaced sets of co-operating pairs of refractory clamping and spacing members operatively engaging said resistor member, and means extending through co-operating pairs of refractory members only laterally of the plane of the resistor for holding said refractory members in proper operative positions.

2. In an electric heating unit, in combination, a resistor member preformed to comprise a plurality of substantially parallel-extending return-bent straight portions, and a plurality of spaced sets of refractory clamping and spacing members operatively engaging said resistor member, each set comprising two rows of staggered pairs of refractory members, and means extending through each pair only to hold them against said resistor.

In testimony whereof, I have hereunto subscribed my name this 15th day of January 1924.

ALVIN D. KEENE.
